CLAIM

The ornamental design for a hammer handle, as shown and described.

DESCRIPTION

FIG. 1 is a perspective view of a hammer handle showing my new design;

FIG. 2 is a bottom plan view thereof;

FIG. 3 is a top plan view thereof;

FIG. 4 is a right side elevational view thereof;

FIG. 5 is a rear elevational view thereof; and,

FIG. 6 is a front elevational view thereof.

The left side of the hammer handle is a mirror image of the right side.

The hammer head and grip shown in broken lines in FIGS. 1–6 are not part of the claimed design.

1 Claim, 2 Drawing Sheets

Matter enclosed in heavy brackets [ ] appears in the original patent, but forms no part of this reissue; matter printed in italics indicates the additions made by reissue.
